UNITED STATES PATENT OFFICE.

JOHN F. WHITE, OF CHICAGO, ILLINOIS, ASSIGNOR, BY MESNE ASSIGNMENTS, TO WHITE PRODUCTS COMPANY, OF CHICAGO, ILLINOIS, A CORPORATION OF ILLINOIS.

HOOD-FASTENER.

1,300,796.

Specification of Letters Patent. Patented Apr. 15, 1919.

Application filed January 2, 1917. Serial No. 140,005.

To all whom it may concern:

Be it known that I, JOHN F. WHITE, a citizen of the United States, residing at Chicago, in the county of Cook and State of Illinois, have invented certain new and useful Improvements in Hood-Fasteners, of which the following is a specification.

The invention has to do with the provision of a simple, sightly, convenient and wholly efficient means for latching and locking engine hoods or other structures involving similar conditions.

The characteristic features of the invention are the dependable latching and unlatching of the device by the natural manipulation of the same in the closing and opening of the hood without the necessity of thought on the part of the operator; the maintenance of a closure under normal conditions secure against accidental release by reason of jar or otherwise; the ready response of the latch to the act of opening and closing the hood under all working conditions; the protection of the latch and lock against the weather and unwarranted manipulation by the placing of the working parts of the same within the hood; the provision of an operating handle outside the hood readily accessible, and preferably removable to constitute of the latch an efficient lock; and many other advantageous features of construction and operation which will appear from the following description thereof read in connection with the accompanying drawings wherein are shown preferred and modified embodiments, it being understood that the drawing and description are to be taken in an illustrative sense and not unnecessarily limiting the invention.

40 In the drawing—

Figure 1 is a vertical section through one embodiment of the invention including a portion of the engine hood and of the frame;

45 Fig. 2 is an inside elevation of the same; Fig. 3 is a horizontal section on the line 3—3 of Fig. 1;

Fig. 4 is a vertical section through a modified embodiment of the invention;

50 Fig. 5 is an inside elevation of the same; Fig. 6 is a horizontal section on the line 6—6 of Fig. 4;

Fig. 7 is a vertical section through yet another embodiment of the invention;

Fig. 8 is an inside elevation of the same; 55 and

Figs. 9 and 10 are horizontal sections on the lines 9—9 and 10—10 respectively of Fig. 7.

Having reference first to Figs. 1, 2 and 3 60 of the drawing, the lower portion of the engine hood is represented at 11 and the frame at 12, the latter having suitably secured thereto by means of screws 13 or otherwise a keeper bracket 14 having a cross member 15 65 with which the latch is adapted to engage. The bracket 16, attached to the hood wall 11, has an outstanding yoke portion comprising a cross member 17 and parallel side members 18. Cross member 17 is provided 70 with a slot 19 extending perpendicularly to the hood wall 11 and side members 18 cut away as indicated at 20 from a point of support for the arms 21 of the U-shaped hanger, the lower cross member 22 of which is slot- 75 ted similarly to cross member 17. The slots 19 and 23 serve as bearings or guides for the shank 24 of latch 25. Within the yoke 17, 18 and about the shank 24 of the latch is mounted an abutment plate 26 which is provided with a slot 27 having a width at least as great as the breadth of the shank 24 and a length somewhat greater than the breadth of said shank to enable the said plate to be placed upon the shank over the spurs 28 80 which extend laterally from said shank and to be then turned through an angle of 90° to the position shown in Fig. 2, in which position the spurs 28 engage with the plate and prevent downward movement of the 85 shank independent of the plate. The plate 26 has upstanding ears 26* which abut against the cross member 17. Between the abutment plate 26 and the cross member 22 of the hanger 21 and about the shank 24 is 90 disposed a compression spring 29.

Slidably mounted within the yoke bracket 16 is an operating rod 30, the lower portion of which is provided with two laterally extending inwardly turned prongs 31, 32 100 which embrace the lower portion of the latch shank 25, prong 31 embracing the latch shank above the head of the latch indicated at 33 and the prong 32 embracing the same

alongside the latch head and extending transversely of the throat 34 of the hook below the beak 35. The inwardly turned portion of the prong 32 may advantageously lie 5 within the throat 34 of the latch head.

As illustrated in Figs. 1, 2 and 3 of the drawings the upper terminal portions of the shank 24 of the latch and the operating rod 30 are substantially conterminous and 10 slightly spaced apart in a line perpendicular to the wall 11 of the hood. The upper end of the shank 24 is apertured at 36 while the upper end of the rod 30 is outwardly turned as indicated at 37, extending to the exterior 15 of the hood through a suitable opening 11^a provided therein. The operating handle or key 38 has a hooded portion provided with parallel spaced side walls 39 which are apertured at 36 in register with the aperture 20 of the shank 24 to receive the cotter pin 40 by which the shank 24 is attached to the key 38. The hooded portion of the key is likewise apertured and provided with a cross pin at 41, this pin taking under the out turned end 37 of the operating rod 30 as 25 illustrated in Fig. 1.

It will be observed that all of the operating parts of the lock are disposed within the hood 11 where they are protected from 30 the weather and are also subject to constant automatic lubrication by means of oil splashed from the engine. They are also protected from injury without the necessity of providing a special latch casing for the 35 housing of the movable parts. In the process of manufacture and assembling, the bracket is riveted to the hood, the hanger 21 and the spring 29 and the abutment plate 26 are placed about the shank 24 of the latch 40 and the upper end of the shank is passed through the slot 19, the upper ends of the hanger 21 are snapped into the opening 20, prongs 31 and 32 of the operating rod 30 are caused to engage the lower ends of the 45 latch and the upper portion of the operating rod is passed through the bracket with the out turned end 37 projecting from the hood. All of these parts may be coated with enamel or paint or the like by dipping at one operation. The handle or key 38 may be finished 50 differently, as for instance, by nickel plating and is assembled by merely inserting the key through the slot in the hood and threading the cotter pin through the aperture 36 of the key and shank and bringing the pin 41 beneath the out turned portion 55 37 of the operating rod.

Assuming the hood to be closed, with the parts in the position indicated in Fig. 1, the operator places his finger beneath the outwardly extending portion of the key and exerts a lifting or upward pressure. The resulting tendency is for the operating rod 30 to move upwardly and the latch shank 60 24 to move downwardly and for the whole

to move outwardly about the hood hinge 42 as a pivot. As the latch moves downwardly relative to the keeper 14 its beak 35 is brought to a point below the cross member 15 of the keeper thus releasing the beak and 70 permitting the latch together with the hood to swing outwardly, the keeper member 15 riding upon the prong 32 of the operating rod. The upward pressure upon the handle 38 having been relieved the compression 75 spring 29 relaxes and restores the parts to the position indicated in Fig. 1, that is to say with the prong 32 underlying the throat of the latch. As the hood is dropped to its closed position, the operator bearing 80 down on the handle 38 causes the hinged portion 11 of the hood to swing inwardly about its pivot 42 bringing the inclined face 43 of the latch head into line vertically with the cross member 15 of the keeper. Continued downward pressure upon the handle 85 38 causes the inclined face 43 of the head to ride upon the keeper member 15, the hood moving outwardly to a slight extent upon the hinge 42, until the beak passes the 90 keeper member 15 and allows the said member to enter the throat of the latch above the prong 32. During the downward pressure on the handle 38 the spring 29 is again compressed and after the beak of the hook 95 passes the keeper, the reaction of the spring causes the hook to move upwardly and the throat of the same to engage the keeper 15.

It will be observed that in the opening of the hood the releasing of the latch is effected by the natural upward movement of the handle 30 under the pull of the operator, no regard being paid by him to the movement of the several parts by which the latch is released; whereas as the hood is closed, 100 the latch is secured by a natural downward pressure upon the handle without the necessity of giving any thought to the engagement of the parts.

Having reference now to Figs. 4, 5, and 6 110 of the drawings, it will be observed that the parts 11 to 20 inclusive are the same as in the former construction. Here, however, the hanger for the spring 29 is omitted and in lieu thereof is provided a rigid abutment 115 bracket 44 with a superposed washer 45 upon which the spring 29 bears. Many other parts of the construction are identical and are represented in these figures by corresponding reference numerals, but the operating rod 30 being guided within the bracket 44 does not require the in-turned 120 portions of the prongs 31 and 32, these prongs being in this instance straight and indicated by the reference numerals 46 and 47. In this form of construction, also, the key indicated at 48 is detachable and capable of being removed entirely from the rest of the structure. To this end while it is provided with a cross pin 49 similar to the 130

former construction, it is provided with registering slots 50 instead of the apertures for engagement with the upper end of the latch shank, the said shank being provided with a cross pin 51 in lieu of the cotter pin.

In this form of construction the mode of operation is substantially the same as in that previously described, but it has the further distinguishing characteristics that, 10 the hood being closed, the operator may withdraw the key 48 from the hood and place it in his pocket leaving the engine hood free of danger from unauthorized tampering, it being practically impossible 15 for anyone without a suitable tool or key to so manipulate the latch as to open the hood, thus constituting of the latch a dependable lock. When the bearer of the key returns to the car and wishes to open the 20 hood all that is necessary is to insert the same to the slot in the hood and engage the pins 51 and 49 with the slot 50 and the out-turned end 37 of the operating rod respectively.

25 Referring now to Figs. 7, 8, 9 and 10, we find here a still further modification which in many respects has advantages over those previously described, embodying as it does the important features of the former 30 construction in combination. In this form of construction is utilized both the hangers 21 and also a bracket 54, this bracket being somewhat similar to the bracket 44 in that it is rigidly attached to the hood and serves 35 as a vertical guide for the operating rod 30 and for the shank 24 of the latch. This bracket also acts as an abutment for the spring 29 and as an anchorage for the lower 40 end of the hanger 21. Here the key is likewise detachably connected with the operating rod and latch shank, but the outer portion is of slightly different shape being curled inwardly as indicated at 55 to make the same more convenient for carrying in 45 the pocket.

I claim:

1. In a device of the class described, the combination with a hinged member of an engine hood, of a latch rigidly mounted on 50 said member and arranged to coöperate with the hinge to engage a fixed anchorage within the hood, and a handle for said latch operable from without the hood to release the latch in the act of raising the hood.

55 2. In a device of the class described, the combination with a hinged member of an engine hood, of a latch rigidly mounted on the interior of said member and arranged to coöperate with the hinge to engage a 60 fixed anchorage within the hood, and a hood operating handle connected to the latch and extending to the exterior of the hood.

65 3. In a device of the class described, the combination with a hinged member of an engine hood, of a latch mounted on the

interior of said member and arranged to engage a fixed anchorage within the hood and an operating handle extending to the exterior of the hood, the handle arranged in the act of lifting the hood to simultaneously release the latch and by depressing to simultaneously engage the latch.

4. In a device of the class described, the combination with a hinged member of an engine hood, of a latch mounted on the interior 75 of said member and arranged to engage a fixed anchorage within the hood, and an operating handle extending to the exterior of the hood, said handle removably associated with the latch whereby to constitute 80 of the same a key and of the latch a lock to prevent unauthorized opening of the hood.

5. In a device of the class described, the combination with a hinged member of an engine hood, of a keeper and latch hook 85 mounted within the hood one on the hinged member and the other fixed, and relatively movable toward each other, a spring pressing the hook away from the keeper, an operating member movably associated with 90 the hook and having a portion extending across the throat and below the beak of the hook, the operating member operable from without the hood to expel the hook from the keeper in the act of opening the hood and 95 to engage the hook with the keeper in the act of closing the hood.

6. In a device of the class described, the combination with a hinged member of an engine hood, of a keeper and latch hook 100 mounted within the hood one on the hinged member and the other fixed, and relatively movable toward each other, a spring pressing the hook away from the keeper, an operating member movably associated with the 105 hook and having a portion extending across the throat and below the beak of the hook, and a handle attached to the hook and operating member and extending to the exterior of the hood, whereby pressure on the 110 handle in the act of closing the hood will engage the hook with the keeper and an upward pull on the handle in the act of opening the hood will depress the hook and lift the operating member to expel the hook 115 from the keeper.

7. In a device of the class described, the combination with a hinged member of an engine hood, of a stationary keeper within the hood, a latch hook mounted within the hood on the hinged member and swinging therewith to and from operable relation to the keeper, a spring pressing the hook away from the keeper, an operating member movably associated with the hook and having a portion extending across the throat and below the beak of the hook, and a handle connected with the hook and the operating member and extending to the exterior of the 120 hood, the parts so assembled and arranged 125

- that pressure on the handle in the act of closing the hood will engage the hook with the keeper and an upward pull on the handle in the act of opening the hood will depress the hook and lift the operating member to expel the hook from the keeper.
8. In a device of the character described, the combination with a hinged member of an engine hood, of a stationary keeper within the hood, a bracket attached to the hinged hook member, a hook latch mounted on the interior of the hinged hook member with its head in operative relation to the keeper and its shank slidable within the bracket, a spring abutting on the bracket and holding the latch engaged with the keeper, an operating rod movably associated with the hook latch and slidable within the bracket and having a portion extending across the throat of the hook below the beak of the same, and an operating handle connecting the shank of the hook and the operating rod and extending to the exterior of the hood, the parts so assembled and arranged that downward pressure on the handle in the act of closing the hood engages the hook with the keeper and an upward lift thereon in the act of opening the hood expels the hook from the keeper, the operating handle removably associated with the latch element whereby to constitute of the same a key and of the latch a lock to prevent unauthorized opening of the hood.
9. In a device of the character described, the combination with a hinged member of an engine hood, of a stationary keeper within the hood, a bracket attached to the hinged hook member, a hook latch mounted on the interior of the hinged hook member with its head in operative relation to the keeper and its shank slidable within the bracket, a spring abutting on the bracket and holding the latch engaged with the keeper, an operating rod movably associated with the hook latch and slidable within the bracket and having a portion extending across the throat of the hook below the beak of the same, and an operating handle connecting the shank of the hook and the operating rod and extending to the exterior of the hood, the parts so assembled and arranged that downward pressure on the handle in the act of closing the hood engages the hook with the keeper and an upward lift thereon in the act of opening the hood expels the hook from the keeper, the operating handle removably associated with the latch element whereby to constitute of the same a key and of the latch a lock to prevent unauthorized opening of the hood.
10. In a device of the class described, the combination with a hinged member of an engine hood, of a latch mounted on the interior of said member and arranged to engage a fixed anchorage within the hood, and a removable key operatively associated with the latch whereby to lock said latch.
- In testimony whereof I have hereunto signed my name in the presence of two subscribing witnesses.
- JOHN F. WHITE.

DISCLAIMER

1,300,796.—*John F. White*, Chicago, Ill. HOOD-FASTENER. Patent dated April 15, 1919. Disclaimer filed February 10, 1931, by the assignee, *Chicago Forging & Manufacturing Co.*

Enters the following disclaimer, to wit:

Your petitioner disclaims from claims 1, 2, and 3 of said Letters Patent all fasteners except fasteners used in connection with an engine hood of an automobile of the type referred to and described in said Letters Patent, having the "hinged member" upon which the "latch" is "rigidly mounted" movable in two directions when being moved to its open position, the latch, when engaging the "fixed anchorage within the hood," holding the member to which it is connected from movement in said two directions.
